Taiwan Patent Office, "Office Action", Aug. 30, 2022, Taiwan.

Primary Examiner — Marie D. Fast Horse(74) *Attorney, Agent, or Firm* — Troutman Pepper Locke LLP; Tim Tingkang Xia, Esq.(57) **CLAIM**

The ornamental design for a "seat body of keyboard dock" as shown and described.

DESCRIPTION

FIG. 1 is a top, front, and right side axonometric view of a seat body of keyboard dock, showing my new design; FIG. 2 is a bottom, front, and left side axonometric view thereof;

FIG. 3 is an atop, rear, and left side axonometric view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the figures illustrate portions of the seat body of keyboard dock that form no part of the claimed design.
